UNITED STATES PATENT OFFICE.

CHARLES GREY HILL, OF NOTTINGHAM, ENGLAND.

DESIGN FOR BRAID OR RUCHING.

SPECIFICATION forming part of Design No. 21,170, dated November 10, 1891.

Application filed October 7, 1891. Serial No. 408,020. Term of patent 3½ years.

To all whom it may concern:

Be it known that I, CHARLES GREY HILL, a subject of the Queen of Great Britain, residing at Nottingham, England, have invented and 5 produced a new and original Design for Braids and Ruchings, of which the following is a specification, reference being had to the accompanying drawings, forming a part thereof.

Figure 1 is a front elevation of a ruching 10 embodying the features of my invention, and Fig. 2 is a rear elevation thereof.

The principal feature of the design consists in ornamental figures A, arranged in longitudinal grouping covering the edge of a body- 15 figure B, simulating a strip of fabric. The ornaments A are located diagonally upon the body-figure in contact with each other, con-

cealing the edge of the body-figure and appearing, when viewed separately in front elevation, as essentially rectangular in general 20 contour. When viewed collectively, a spiral or wave-like effect is obtained. When the ornaments are observed from the back, as shown in Fig. 2, the effect is that of a series of loop-like figures. 25

I claim—

A design for a braid or ruching, substantially as herein shown and described.

CHARLES GREY HILL.
